SHOE AND METHOD OF MAKING THE SAME

Joseph Le Burgio, Marion, Ill.

Application June 19, 1933, Serial No. 676,491

4 Claims. (Cl. 12—142)

This invention relates generally to shoes and method of making the same and has for its prime object the provision of a shoe structure embodying a one-piece sole, in the construction of which merely one lasting operation is requisite, and in which the upper of the shoe is secured directly to the outsole, an inner sole being eliminated.

My invention has for another object the provision, in a shoe construction of the character described, of a one-piece sole suitable for the manufacture of both welt and glued or so-called "Compo" shoes, and in either case highly suitable especially, though not exclusively, for the manufacture of shoes for feminine wear, in which a relatively light, flexible sole is desirable or requisite.

And with the above and other objects in view, my invention resides in the unique method of shoe construction and in the novel features of form, construction, arrangement, and combination of parts presently described and pointed out in the claims.

In the accompanying drawing,—

Figure 1 is a bottom plan view, partly broken away, of a shoe of the welt-type, embodying one form of my invention;

Figure 2 is a fragmentary sectional view taken approximately along the line 2—2, Figure 1;

Figure 3 is a bottom plan view, partly broken away and in section, of a shoe of the glued or "Compo" type, embodying another form of my invention; and

Figure 4 is a fragmentary sectional view taken approximately along the line 4—4, Figure 3.

Referring now more in detail and by reference characters to the drawing, which illustrates practical embodiments of my invention, A designates a shoe of the welted-type which includes the usual upper 1, for which is provided a one-piece sole 2 of suitable material and preferably contoured to the desired outline, the sole 2 at its rear portion being suitably marginally skived or beveled, as at 3, and finished to provide a heel-seat 4.

The sole 2 throughout its entire fore part, from the heel-seat 4 to the toe of the shoe, is slit inwardly and thereby provided with a channel 5, which extends around the lateral side or peripheral face of the sole 2 and which is disposed preferably somewhat nearer to the inner or flesh side 6 of the sole 2 than to the outer or grain side 7 thereof.

The channel 5 splits the marginal portions of the sole 2 into an upper or inner flap 8 and an opposing lower or outer flap 9, each coextensive with the channel 5, which latter is of sufficient depth to allow the stitching of the upper 1 to the outer flap 9, as presently appearing, in such manner as to leave the central portion of the sole 2 intact, integral, and of a single thickness.

On its flesh side 6, the sole 2 is provided with a recess or groove for receiving a shank-piece or metallic stiffener 12, which extends in suitable position from the heel-seat 4 to the break 11 of the shoe.

The stiffener 12 is mounted in its groove and attached to the sole 2 by suitable fastening elements such as tacks 10, and a shank-cover 13, of suitable material is laid on the last (not shown), for extending substantially over and from the heel-seat 4 to the break 11 of the shoe. The sole 2 and its attached stiffener 12 is mounted on the last over the cover 13, and the shoe-upper 1 is then arranged about, or built upon, the last.

The rear portion of the upper 1 is preferably stretched or pulled to and over the bevel 3 of the heel-seat 4, and suitable fastening elements, such as lasting nails 14, are driven through the margin 15 of the upper 1 and sole 2 and clinched in the cover 13 for attaching the same securely together, as best seen in Figures 1 and 2.

Into the channel 5 is preferably applied a suitable filler or plastic material 16, and the balance of the upper 1, from the heel-seat 4 to the toe of the shoe, is stretched over the last, with the marginal portion of the upper 1 foldably in V-shape, as at 17, inserted into the channel 5. The free margin 18 of the upper then resides upon the inside face of the outer flap 9, and is skived suitably so as to diminish in thickness toward the edge thereof.

A welt 19 is then pressed or inserted into the fold 17 of the upper 1. The welt 19 differs, so far as I am aware, from the usual form of welt in being of a wedge-shaped cross-section, its lower face being skived and preferably channeled, as at 20, for providing a lip 21 of full thickness of the welt 19 at the outer margin thereof, the channel 20 being complementary to the beveled margin 18 of the upper 1 for overlying and firmly engaging the same with the upper face of the outer flap 9 when the lip 21 resides snugly flushwise with the outsole margin.

A suitable securing means, as a line of stitching 22, is then run through the welt 19, the upper margin 18, and the sole-flap 9 for attaching the margin 18 to the lower wall of the slit or channel 5 and securing the sole 2 to the upper 1, as best seen in Figure 2.

Thereafter, the heel 23 may be applied to the heel-seat 4, and the other manufacturing operations applied to the shoe in the usual and customary manner, for forming the finished shoe-product.

It will be seen that, by my improved shoe-construction, the shoe A has the advantage of a welt shoe, inasmuch as merely a single lasting thereof is required, while, on the other hand, the use of an inner sole, heretofore so far as I am aware, required in welted-shoes, is eliminated.

55

60

B designates a shoe-construction of the glued or "Compo" type, which includes the usual upper 1', for which is provided a one-piece sole 24 of suitable material and preferably contoured 5 to the desired outline in the usual manner. In its rear portion the sole 24 is split completely across its width and thereby provided with an inner tongue 25 on its flesh side 26 and an outer tongue 27 on its grain side 28, each tongue 25, 27 10 preferably extending from the break 29 of the shoe rearwardly to the heel thereof.

The rear margins of the tongues 25, 27, from the break 29 to the heel of the shoe are suitably skived and beveled, as at 30, 31, respectively, the 15 bevel 30 of the inner tongue 25 overlapping the bevel 31 of the outer tongue 27, the latter being also suitably finished for providing a heel-seat 32. The concealed face of the inner tongue 25 is provided with a longitudinal groove or channel 33 extending from the break 29 approximately to the heel-seat 32 for reception of a shank-stiffener 34, as best seen in Figures 3 and 4.

The fore part of the sole 24, from the break 29 to the toe of the shoe, is slit inwardly and thereby 25 provided with a channel 35, which extends around the lateral side of peripheral face of the sole 24, and which is disposed approximately equally intermediate of the flesh side 26 and grain side 28 thereof.

30 The channel 35 splits the marginal portions of the sole 24 into an upper or inner flap 36 and an opposing lower or outer flap 37, each coextensive with the channel 35, which latter is of sufficient depth to admit the marginal portions of the 35 upper 1', as will presently appear, in such manner as to leave the central portion of the sole 24, under the ball of the foot, intact, integral, and of a single thickness.

The sole 24 being provided as described, the 40 stiffener 34 is by suitable nails 38 attached to the inner tongue 25, so as to be in registration with the groove 33 in the outer tongue 27. The sole 24 is then suitably mounted on the last (not shown), and the tongues 25, 27, are securely glued or 45 cemented together, whereby the integrity of the sole 24 is substantially restored, and the stiffener 34 is snugly enclosed in its proper position between the tongues 25, 27, thus obviating the need of a stiffener-cover, as employed in the shoe A 50 hereinbefore described.

The upper 1' is then arranged about or built upon the last, and the portion of the upper 1' from the break 29 to the heel of the shoe is glued and then stretched or pulled to and over preferably merely the bevel 30 of the tongue 25, suitable fastening elements 38', as lasting nails or staples, being driven through the margin 39 of the upper 1', and clinched in the inner tongue 25 for retaining the upper 1' in position during 60 the hardening or setting of the glue or cement by which the upper 1' is attached to the sole 24 in the customary manner.

The margin 40 of the portion of the upper 1' from the break 29 to the toe of the shoe is suitably beveled or skived and likewise glued, and the upper 1' is then stretched over the last with the margin 40 neatly inserted in the channel 35 of the sole 24, the parts being retained in such position by any suitable means, not shown, during the hardening or setting of the adhesive for attaching the margin 40 to the lower wall, or if desired, to both walls of the slit or channel 35, and the sole 24 to the upper 1'.

The heel 41 is then attached to the heel-seat 32, and the manufacture of the shoe B is thereafter completed in the manner well known to those skilled in the art.

It will be seen that, in the glued-shoe B, all 5 stitching is omitted, and reliance is had on the cement alone for securing and maintaining the upper in the interior of the sole between the flap-portions 25 and 27 and also for securing said flap-portions in place.

10 It will be understood that other changes and modifications in the form, construction, arrangement and combination of the several parts of my new shoe constructions and in the methods of manufacturing the same may be made and substituted for those herein shown and described without departing from the nature and principles of my invention.

Having thus described my invention, what I claim and desire to secure by Letters-Patent is,— 20

1. A shoe comprising, in combination, a sole having a slit extending inwardly from its peripheral face intermediate its inner and outer sides, said slit dividing the marginal portion of the sole into upper and lower flaps, an upper having its 25 margin beveled and foldably disposed in said slit, and means including a welt disposed in the slit and within the folded margin of the upper for securing the upper to the lower sole-flap, the welt having a beveled face for engaging the beveled face of the margin of the upper. 30

2. A shoe comprising, in combination, a sole having a slit extending inwardly from its peripheral face intermediate its inner and outer sides, said slit dividing the marginal portion of the 35 sole into upper and lower flaps, an upper having its margin beveled and foldably disposed in said slit, and means including a welt disposed in the slit and within the folded margin of the upper for securing the upper to the lower sole-flap, the welt having a beveled face for engaging the beveled face of the upper-margin and a lip for engaging the lower sole-flap. 40

3. The method of making a shoe which consists in inwardly forming a slit in the peripheral 45 face of an outsole and thereby dividing the margin of the sole into opposing inner and outer flaps, lasting the shoe, folding inwardly the marginal portion of the shoe upper between the upper and lower flaps, beveling the free margin of the 50 upper, disposing a wedge-shaped welt within the folded upper-margin for overlying the beveled portion thereof, and then stitching together the welt, the upper, and the outer flap of the sole.

4. The method of making a shoe which consists in forming a heel-seat on an outsole, inwardly forming a slit in the peripheral face of the outsole from the heel-seat to the toe of the shoe and thereby dividing such marginal portion of the sole to include opposing upper and lower 60 flaps, forming a groove in the inner face of the outsole from the heel-seat to the brake of the shoe, mounting a shank-stiffener in said groove, concealing the shank with a cover extending from the break of the shoe to and over the heel-seat, 65 lasting the shoe, disposing the marginal portion of the upper in said slit, nailing the rear-part of the upper, the sole, and the cover together at the heel-seat of the shoe, and then stitching the margin of the upper to the lower flap of the sole. 70
